UNITED STATES PATENT OFFICE.

WILLIAM F. POHLMANN, OF CHICAGO, ILLINOIS, ASSIGNOR TO F. W. MATEER & CO.,
OF CHICAGO, ILLINOIS, A CORPORATION OF ILLINOIS.

SAFETY DEVICE FOR LAUNDRY MACHINES.

Application filed July 31, 1925. Serial No. 47,197.

The present invention relates to improvements in power driven laundry machinery, and has particular reference to a new and useful safety device which will prevent the cover from being opened when the machine is in operation, and which when the cover is open will prevent the machine from being operated.

The general objects of my invention are to provide a new and improved safety device which can be readily applied to existing laundry machines, which is simple and inexpensive in construction, which utilizes standard parts having other functions on the machine, and which is efficient in operation.

Further objects and advantages will become apparent from the following description taken in connection with the accompanying drawings wherein:

20 Figure 1 is a side elevational view of a washing machine having my invention applied thereto.

Fig. 2 is a fragmentary sectional view taken along line 2—2 of Fig. 1.

25 Fig. 3 is an end view of the machine.

Fig. 4 is a fragmentary view of the means for locking the cover of the washing machine in position.

30 Fig. 5 is a fragmentary sectional view taken substantially in the plane of line 5—5 of Fig. 6.

Fig. 6 is a fragmentary sectional view taken substantially in the plane of line 6—6 of Fig. 3.

35 Fig. 7 is a fragmentary sectional view taken substantially in the plane of line 7—7 of Fig. 6.

While the invention is susceptible of various modifications and alternative constructions, I have shown in the drawings and will herein describe in detail the preferred embodiment thereof, but it is to be understood that I do not thereby intend to limit the invention to the particular form disclosed, but aim in the appended claim to cover all modifications and alternative constructions falling within the spirit and scope of the invention.

The washing machine selected for purposes of illustration comprises a cylindrical body 10 supported at opposite ends by frame members 11 and 12, and having an opening 13 therein near its upper forward side arranged to be closed by a sliding cover 14. 50 The body 10 encloses a washing cylinder 15

which is mounted on a shaft 16, and which is adapted to be driven through a large gear 17 on the shaft first in one direction and then in the other. The gear 17 is enclosed in a suitable casing 18 supported by brackets 60 19 on the end of the body 10.

Any suitable means may be provided for driving and reversing the drive of the shaft 16. Preferably I employ the mechanism disclosed in a copending application, Serial No. 65 20,575, filed April 3, 1925 by Robert H. Palm, and myself. This mechanism consists of a shaft 20 journaled in a bracket 21 on the body 10, and having a pinion 22 on one end in mesh with the gear 17. Two 70 pulleys 23 and 24 are loosely mounted on the shaft 20, and are adapted to be driven respectively by belts 25 and 26 connected with a suitable source of power (not shown). The belt 25 is shown as being twisted so as 75 to drive the pulley 23 in a direction opposite to that in which the pulley 24 is driven. Rigidly mounted on the shaft 20 between the pulleys 23 and 24 is a pulley 27 onto and off of which the belts 25 and 26 are adapted 80 to be shifted alternately by a pair of belt shifters or guides 28 and 29. These guides are carried by a bar 30 mounted in an upstanding bracket 31 for reciprocation in a direction parallel to the axis of the shaft 20. 85

Slidable relative to the bar 30 and depending therefrom is a plate 32 having opposed cam surfaces 33 and 34 arranged to be engaged by a projection 35 on a worm wheel 36 suitably journaled in the bracket 31. The 90 worm wheel 36 is arranged to be continuously driven from a worm 37 journaled on the shaft 20 and having a clutch connection at all times with the pulley 24. The latter is constantly driven by the belt 26 which as 95 indicated in Figure 1 is of a width such that even when shifted onto the tight pulley 27 it overlaps the loose pulley 24. Rotation of the worm wheel 36 serves through the projection 35 and cam surfaces 33 and 34 to reciprocate the plate 32 and thereby the slide bar 30 carrying the belt shifter guides 28 and 29. The pulleys 23 and 24 are thus alternately connected with the tight pulley 100 27 for the purpose of rotating the washing cylinder 15 first in one direction and then in the other.

The connection between the plate 32 and the bar 30 comprises a rocker member 38 pivotally mounted on the bar through the 105 110

medium of a bracket 39 and adapted to enter a notch 40 formed in the upper end of the plate 32. When the rocker member 38 is moved upwardly from the position shown in Figure 2 to disengage it from the notch 40 the power transmission is inoperative. To lock said mechanism against operation, the rocker member 38 is adapted to be swung rearwardly into engagement with a notch 41 formed in the upper end of a member 42 on the bracket 31.

Means is provided for manually rotating or inching the cylinder 15. This means comprises a shaft 43 extending eccentrically through a sleeve 44 rotatably mounted in a pair of spaced arms 45 on a bracket 46 secured to the end wall of the body 10. The forward end of the shaft 43 is provided with a hand wheel 47, and the rear end is provided with a worm 48 adapted to be moved into and out of mesh with the gear 18 upon rotation of the sleeve 44 in opposite directions. A hand lever 49 is rigidly mounted on one end of the sleeve 44 to provide means for adjusting the latter. The worm 44 when in engagement with the gear 18 prevents power operation of the machine.

Means is provided for preventing the cover 14 from being opened while the machine is in operation, and for preventing the machine from being operated when the cover is open. This means comprises a lever arm 50 connected at one end through a link 51 to the cover 14, and mounted at its other end on a rock shaft 52 journaled in brackets 53 on the body 10. Rigidly secured on the right end of the rock shaft 52 is an interlocking member in the form of a segmental plate 54. A lever 55 is pivotally mounted in a bracket 56 on the end of the machine, and is formed with an interlocking stop 57 adapted to be moved over the upper edge of the segmental plate 54. The lower end of the lever 55 is formed with a slot 58 fitting loosely over a pin 59. The latter is mounted in the free end of a bracket 60 rigidly secured to the eccentric sleeve 44 for movement therewith and extending across the rear end of the worm 48, and is off-set with

respect to the axis of rotation. When the sleeve 44 is adjusted to move the worm 48 into engagement with the gear 18, the lower end of the lever 55 will be moved away from the end of the body 10, thereby swinging the stop 57 out of the path of the segmental plate 54 and hence permitting the cover 14 to be opened. The worm 48 cannot be moved out of engagement with the gear 18 while the cover is open since the segmental plate 54 is positioned in the path of the stop 57. Since the worm 48 is effectual as a lock to prevent movement of the gear 18, the machine cannot be operated by power while the cover is open.

It will be evident that I have provided an exceptionally simple and inexpensive device for ensuring safety in operating laundry machines. The device is positive in operation, and utilizes mechanism customarily employed for manually inching the cylinder 15 when the machine is inoperative. The safety device prevents the cover from being opened while the machine is in operation, and prevents operation of the machine while the cover is open.

I claim as my invention:

In a machine of the character described, in combination: a body having a closure, a movable member in said body, power transmission for said movable member, said power transmission including a gear, a sleeve rotatably mounted on said body, a shaft eccentrically mounted in said sleeve and having a worm adapted to be moved by angular adjustment of said sleeve into and out of engagement with said gear, a stop member associated with said closure for movement therewith, and a second stop member eccentrically associated with said sleeve for movement into and out of the path of said first mentioned stop member upon adjustment of the sleeve, said stop members being arranged to prevent said closure from being opened when said worm is out of engagement with said gear.

In testimony whereof, I have hereunto affixed my signature.

WILLIAM F. POHLMANN.
